FIG. 1

FIG. 3

UNITED STATES PATENT AND TRADEMARK OFFICE
CERTIFICATE OF CORRECTION

PATENT NO. : Des. 429,308
DATED : August 8, 2000
INVENTOR(S) : Guhring

It is certified that error appears in the above-identified patent and that said Letters Patent is hereby corrected as shown below:

In the description of FIG. 2 on the title page of U.S. Des. 429,308, after “FIG. 2 is a right side view of “delete” another weapon...of FIGS. 1 and 2”
and insert -- the weapon of FIG. 1 --.

In the description of FIG. 3, “perspective view” delete “of the weapon” and insert -- of another weapon constructed in accordance with the teachings of the invention but employing a different scope than the weapon --.

Signed and Sealed this

Tenth Day of July, 2001
